UNITED STATES PATENT OFFICE.

AUGUST PRYM, OF BÜSBACH, NEAR STOLBERG, GERMANY.

FASTENING OF THE SPRING-SOCKETS OF PRESS-BUTTONS.

1,399,319.

Specification of Letters Patent.

Patented Dec. 6, 1921.

Application filed November 23, 1914. Serial No. 873,617.

(GRANTED UNDER THE PROVISIONS OF THE ACT OF MARCH 3, 1921, 41 STAT. L., 1313.)

To all whom it may concern:

Be it known that I, AUGUST PRYM, manufacturer, a citizen of the Empire of Germany, residing at Büsbach, near Stolberg, Villa 5 Waldfriede, in the Empire of Germany, have invented a new and useful Improvement in Fastenings of the Spring-Sockets of Press-Buttons, (for which I have filed an application in Germany Sept. 13, 1913,) of 10 which the following is a specification.

The present invention relates to improvements in separable buttons particularly to spring pressed buttons comprising a socket member and a cap.

15 It is the object of the present invention to provide a button, the socket of which has a turned over edge underneath which the body of a double shank wire spring is held, the shanks of which are guided through incisions in a perforated dome projecting from the center of the socket plate.

Another object of the invention is to provide a separable button the socket member of which and the cap can be united above 25 a piece of fabric by a slight pressure by providing the dome at its top with an opening into which fits the outwardly flared nipple of the cap with an elastic snap as soon as a 30 pressure is exerted upon socket and cap, providing a firm hold which yet may be overcome easily to separate the parts if this is the intention.

In this manner a reliable fastening of the press button part is obtained which may 35 easily be carried out by special machines and which is far superior to the customary sewing both as regards strength and rapidity of execution.

The manner in which the new fastening is 40 effected may be seen in Figures 1 to 5 of the accompanying drawing, in which:

Fig. 1 is a top plan view of the socket plate with the double shank wire spring.

Fig. 2 is a vertical cross-section through the parts shown in Fig. 1.

45

Fig. 3 is a top plan view of the cap.

Fig. 4 is a section through the same, and

Fig. 5 is a vertical cross-section through the socket and cap combined.

In the figures, *a* represents the socket 50 plate, in which a double shank wire spring *b* is arranged and rigidly held by the turned over edge of the plate *a*. From the middle of the plate, the dome *d* projects, which has incisions at *e* in which the two elastic shanks 55 of the wire spring *b* acting on the interior of the dome, can move freely. The top of the dome *d* is perforated at *f*. Into this perforation the hollow outwardly flared nipple *h* in the middle of the inner face of the cap 60 is elastically fitted with a snap action.

I claim:

In a separable button, the combination with a socket plate having a turned over edge, a double shank wire spring rigidly held with its body underneath of said turned over edge in said socket plate, a perforated dome projecting from the middle of the plate provided with incisions, permitting a free movement of the elastic shanks of said 65 wire spring acting on the interior of the dome, a cap, a hollow rivet on said cap and an outwardly flared flange on said rivet adapted to be inserted into the perforation 70 of said dome and to be turned down around the edge of said perforation for tightly gripping the material between the cap and socket plate, substantially as described.

75

AUGUST PRYM.
